UNITED STATES PATENT OFFICE.

FREDERICK H. PERRY, OF BEVERLY, MASSACHUSETTS, ASSIGNOR TO UNITED SHOE MACHINERY CORPORATION, OF PATERSON, NEW JERSEY, A CORPORATION OF NEW JERSEY.

INSOLE.

Application filed August 5, 1918. Serial No. 248,236.

To all whom it may concern:

Be it known that I, FREDERICK H. PERRY, a citizen of the United States, residing at Beverly, in the county of Essex and State of Massachusetts, have invented certain new and useful Improvements in Insoles; and I do hereby declare the following to be a full, clear, and exact description of the invention, such as will enable others skilled in the art 10 to which it appertains to make and use the same.

This invention relates primarily to insoles for boots and shoes and is especially applicable to "manufactured", i. e. laminated or built-up, insoles, although it is not 15 limited in its application to insoles of that type.

In making insoles for welt shoes it has heretofore been customary to provide a 20 feather outside the sewing-rib which is of a uniform cross-sectional thickness and the surface of which lies in the same plane relative to the tread face of the insole. The sewing-rib and feather form together an angle 25 into which the upper materials are lasted. The thickness of the upper materials is not uniform, there being a considerable extra thickness at the toe portion caused by the insertion of the box-toe and additional toe 30 stiffening materials. By reason of this the welt, when seated upon the upper, the shoe being then in inverted position, rests in a higher plane relative to the base of the toe portion of the insole than throughout the 35 remainder of the shoe. Consequently considerable difficulty is experienced by the operator of the inseaming machine in sewing around the toe. If the operator sews "high", which is the natural consequence of the 40 raised position of the welt, a weak inseam results and subsequently when the outsole is attached the latter is held above its proper plane at the toe and the correct line of the shoe is lost. If the sewing-rib is too low to 45 permit the welt to be sewed "high", the operator will tip the shoe so as to sew "full" and the long stitch thus formed through the 50 rib or between substance will be exposed in the welt crease of the completed shoe, producing what is termed a "grinning" inseam which further detracts from the appearance of the shoe. The difficulties due to such a raised position of the welt at the toe are

even more serious when a shoe, and especially one the upper of which is premolded at the toe, is sewn on an automatic machine, as below mentioned. Moreover, similar difficulties may occur at any other portion of the shoe where there is an extra thickness of upper materials.

In view of the foregoing, it is one object of the present invention to provide an improved insole better fitted to receive and compensate for the extra thickness of the upper materials at the toe, or other marginal, portion of a shoe and better fitted to 60 overcome the difficulties above outlined than insoles heretofore known.

In accordance with this object, the invention, in one aspect, consists in an insole having its feather about the toe molded to lie in a different plane from the plane of the adjacent portions of the feather. In the illustrated insole, the feather has a molded toe portion offset into a plane lower than the plane of the adjacent portions, that is to say, a "lower" plane when the shoe is in inverted position for the welt attaching operation, and as shown in the accompanying drawings, but which becomes a "higher" plane when the shoe is in normal upright position, as when worn. When such an insole is incorporated in a welt shoe, the welt lies properly against the sewing-rib and insures an inseam at a uniform height above the tread face of the insole, whereby the proper lines of the shoe are preserved. The molding will extend about the toe substantially from one end of the tip-line to its other end since the 70 box-toe does not extend back of the tip-line. Those skilled in the art will recognize that an insole having the characteristics defined will add quality, accuracy and perfection to 75 shoe-making since its use overcomes all 80 irregularity and lack of uniformity heretofore present in sewing the upper to the insole.

It is important in making welt shoes that the inseam be started at a definite point on 100 the insole so as not to waste the welting and this becomes of especial importance when the inseam is sewed on an automatic welt sewing machine, particularly when making standardized shoes of the general type disclosed in a co-pending application Serial No.

476,659, filed June 11, 1921, in the name of George E. Warren and owned by the assignee of the present application. In such automatic machinery the operating instrumentalities and the shoe are moved relatively through a definite cycle, usually controlled by a pattern, to transfer the point of operation around the shoe and it is obvious that the starting point on the shoe should be 10 properly positioned with relation to the cycle of the machine.

A further object of the invention is to provide a gage on the insole by which the shoe may be placed in a definite predetermined 15 relation to the operating instrumentalities of the machine which is to operate upon it.

In accordance with this object, a feature of the insole comprises a gage secured by providing a forwardly facing abutment or 20 shoulder at the end of the sewing-rib where the inseaming operation is to commence. This will be at that end of the rib which is on the outside of a left sole and at that end of the rib which is on the inside of a right 25 sole. It is preferred that the gage be in the form of an inwardly turned end on the rib thus forming a shoulder inside the rib the forward side of which may be brought into engagement with the channel guide of 30 the inseaming machine before starting the machine and which will not interfere with the usual feed of the shoe by the machine.

The present invention, in so far as the features above described are concerned, is particularly applicable to manufactured insoles 35 which are generally produced from two or more layers of sheet material, since in the process of their manufacture the toe and the rib may readily be molded to the desired 40 shape.

In manufactured insoles it is also desirable to provide a reinforce at the heel end of the insole to prevent the heel nails when the heel is inside nailed from drawing down 45 pits or depressions in the heel seat.

Accordingly, a still further object of the invention is so to fit a manufactured insole formed from sheets of insole material, that a heel-seat reinforce may be inserted without destroying the lines of the shoe or detracting from its comfort to the wearer.

In accordance with this object it is contemplated that a feature of the insole when manufactured of a laminated structure will 50 comprise a transverse molding of the sheet material, forming the insole layers at about the breast line in a manner to raise the surface of the heel seat sufficiently to permit the reinforce to be inserted between the 55 layers while still preserving a smooth sock-surface. The reinforce will be skived at its forward edge to provide as smooth a surface as possible on the ribbed face or sewing-surface of the insole.

60 The invention comprises an insole having

the novel features of construction and the method of manufacturing it hereinafter described and claimed, and illustrated in the accompanying drawings showing the insole in its preferred form, in which:

70 Figure 1 shows a manufactured welt insole, having the features of the present invention, assembled on a last the toe of which is fitted to receive the offset at the toe of the insole; Fig. 2 is a plan of the ribbed or 75 sewing-surface of the insole shown in Fig. 1; Figs. 3 and 4 illustrate the appearance of the inseam at the toe of a shoe when using the old and the new insoles respectively in welt work; and Fig. 5 is a plan of the heel- 80 seat end of the insole with the sock-surface layer turned back to expose the heel-seat reinforce.

85 The invention will be described in its application to the manufactured welt insole illustrated in the drawings although it is to be understood that certain features of the invention are also applicable to others kinds of manufactured insoles or to insoles formed from a blank of leather.

90 The type of insole illustrated in the drawings is a laminated insole for welt shoes composed of three layers of insole material. Although no specific kind of material is essential, it is preferred to use a textile fabric, 95 such as duck, for one outside layer 5 forming the sewing-surface, said layer being provided with a marginal sewing-rib 6, which may be molded therein at the desired location relative to the edge of the insole, and a feather 7. The remaining layers form the body-layers, the other outside layer 8 forming the sock-surface being preferably a leather skiving equal in area to the area of the unribbed or smooth face of the layer 5. 100 The central body-layer 9 is preferably a leather substitute, such as fiberboard of the same area as the layer 8. These layers together form a feather of uniform thickness 105 which is so fitted as to permit the operator of the inseaming machine to sew the seam at a uniform height relative to the face of the insole, thus preserving the correct lines in the finished shoe, as already explained.

110 The layers are provided with an adhesive and assembled between molds through which pressure is applied preferably to shape the layers to the contour of the last bottom, as shown in Fig. 1, at which time the toe and heel-seat may be fitted to receive the extra 115 thickness of upper materials at the toe and the heel-seat reinforce respectively. The fitting at the toe is preferably performed by a molding process which may conveniently take place when the entire insole is molded, as suggested, in which event the molds are 120 so shaped at the toe as to form shoulders 10 and 11 across the feather at about the tip-line and to press the entire toe portion 12 of the margin or feather into a higher and 125 130

different plane from the adjacent portions thereof at the sides of the forepart. This forms a marginal offset on the sock-surface which is raised in a direction away from the ribbed face of the insole and also forms a corresponding offset in the ribbed face of the insole at the feather and around the toe. Consequently the last on which the insole is assembled must be provided with a marginal rabbet about the toe to receive the offset portion of the insole, as shown at 13 in Fig. 1 where the toe of the last is broken away. In molding the feather as just described the offset produced is of sufficient depth to compensate for the extra upper materials at the toe, comprising the box-toe, its lining, the tip or other pieces. The advantage accruing from fitting the insole in the manner just described will be apparent to those skilled in the art from an inspection of Figs. 3 and 4. Fig. 3 shows an inseam sewed "high" and the consequent distortion in the line of the welt crease due to the abrupt rise at the toe line on to the box toe where an insole feather of uniform thickness is not molded, and Fig. 4 shows the even line of the inseam obtained when the insole of the present invention is used, thus preserving the correct line of the welt crease and providing an even surface on which to lay the outsole. A particular advantage of the present mode of fitting the toe of an insole to obtain the results just adverted to is that no part of the feather thickness is removed, thus preserving in the shoe the original uniform edge thickness and consequently its entire strength.

A further feature of the insole of the present invention as used for welt shoes resides in the formation of the sewing-rib at the end where the inseaming operation is to commence, with a gage 14 in the form of a transverse shoulder the forward side of which may be brought against that side of the channel guide of the inseaming machine which faces in the direction in which the shoe is fed during the inseaming operation. The shoulder is so located longitudinally of the insole that when positioned as above described the inseam will be started at the correct point, as indicated above, with the result that the shoulder will not interfere with the feeding of the shoe to the left, as shown in Figs. 1 and 2. This, as will be recognized by those skilled in the art, is of especial importance when making shoes on automatic machinery. Preferably the gage 14 is formed as a hook from an inwardly turned portion of the sewing-rib and in making a manufactured insole, such as has been described, it may be molded as a bead in the sewing-layer 5 at the same time that the rib is molded therein.

While an insole having such a gage forms a part of the present invention, the method

of making shoes herein disclosed in which such an insole may be advantageously employed for locating the insole and connecting shoe parts relatively to an instrumentality for operating on the shoe, is not herein claimed but that method, and also a machine adapted for use in practising that method, are claimed in an application Serial No. 637,039, filed May 7, 1923, by George E. Warren and owned by the assignee of the present application.

It is desirable in manufactured insoles of all types to reinforce the heel-seat, since the strength of the materials used is not sufficient to prevent the heel nails if driven from the inside from drawing down pits or depressions in the heel-seat. The reinforce is preferably incorporated in such a way as not to cause a protuberance at the heel-seat which would render the sock-surface of the insole uncomfortable to the wearer of the shoe. As shown, therefore, the reinforce is inserted within an offset heel-seat formed on the opposite side of the insole so as to retain the smooth sock-surface as shown in Fig. 1. The offset is produced by forming a transverse shoulder 15 at about the breast line which may conveniently be molded in the insole material at the same time the shoulders 10 and 11 are molded therein. The heel-seat reinforce 16 is preferably inserted between the two body-layers prior to the molding operation and as a result the molding operation preserves the plane heel-seat on the sock-surface layer because the space between the layers, formed by the molding of the shoulder 15, is completely filled by the reinforce. In Fig. 5 the reinforce, because it is preferably made of relatively hard material, is shown as provided with nail holes for inside heel nailing, the sock-surface layer 8 being turned back to expose the reinforce. It is contemplated that this layer may be turned back in this manner after the shoe has been assembled and is ready for the heel attaching operation and then after that operation turned down on to the reinforce again to cover the heel nails. The reinforce is also shown as provided with central jig holes which, however, do not form a part of the present invention, but are utilized in the practice of the method of making shoes forming the subject-matter of the Warren application Serial No. 476,659, above referred to.

The reinforce is preferably skived at its forward edge as shown in Fig. 1 to fit as neatly as possible beneath the offset and to avoid an abrupt rise on the feather where the welt ends are butted and secured.

The nature and scope of the invention having been indicated and its preferred embodiment having been specifically described what is claimed as new, is:

1. An insole having a marginal sewing-

- rib and a feather outside said rib throughout the shank and forepart, the portion of said feather about the toe being molded to lie in a different plane relative to the adjacent portions thereof.
2. An insole having a marginal sewing-rib and a feather of uniform edge thickness outside said rib throughout the forepart, said feather about the toe of the forepart lying in a different plane from the portions thereof at the sides of the forepart.
3. An insole having a marginal sewing-rib and a feather outside said rib throughout the shank and forepart, said feather at the toe portion of the forepart being molded to form an offset about the toe in a direction away from the ribbed face of the insole.
4. An insole having a marginal sewing-rib extending throughout the shank and forepart, said rib at one end terminating in a sharply defined inwardly turned portion to form a gage by which the starting point of the inseam may be determined.
5. An insole having a marginal sewing-rib extending throughout the shank and forepart and a forwardly facing, abrupt shoulder at one end of the rib which is adapted to be placed against one side of the channel guide of an inseaming machine to determine the starting point of the inseam.
6. A manufactured insole comprising a plurality of layers of insole material one of which is provided with a marginal sewing-rib located inside the edge thereof to form a feather, the other layer or layers being secured to the unribbed face of said first layer to form the body of the insole and a feather of requisite thickness, said feather being offset at each side of the forepart forward from about the ends of the tip-line to locate its surface about the toe in a different plane from the adjacent portions thereof.
7. A manufactured insole comprising a plurality of layers of insole material one of which is provided with a marginal sewing-rib, having one end in the form of an inturned hook, formed by molding a bead in the material inside the edge thereof.
8. An insole having a marginal sewing-rib extending throughout the shank and terminating substantially at the breast line, and an abrupt shoulder extending inwardly beyond the rear portion of the rib at one side only of the insole by which the starting point of the inseam may be determined.
9. An insole having a marginal sewing-rib and feather extending to the heel-seat, said heel-seat being offset on one face of the insole and the feather at the toe being offset in a direction away from the ribbed face of the insole.
10. A manufactured insole comprising a plurality of layers of insole material at least one of which is provided with a transverse molded shoulder at about the breast line forming an offset heel-seat, and all of which are provided with a molded shoulder within the margin about the toe forming an offset feather at that portion of the insole.
11. An insole having an edge of uniform thickness about the forepart, and its margin about the toe molded to lie in a different plane relative to the adjacent portions thereof.
12. An insole having a smooth sock-surface except at its margin about the toe which lies in a higher plane than adjacent portions of the sock-surface, the opposite face of the insole being correspondingly offset or raised to provide space beneath the insole for the inflated upper materials.
13. An insole having a marginal strip around one end and outside of the body of the insole and molded to lie in a higher plane than, but substantially parallel to, the plane of the adjacent marginal portions of the forepart of the insole.
14. A manufactured insole comprising a plurality of layers of insole material having a relatively narrow marginal portion around the toe molded and offset slightly to lie in a different plane from the adjacent marginal portions of the forepart back of the tip-line of the insole to compensate for an extra thickness of upper materials at the corresponding portion of the shoe in which the insole is to be incorporated.
15. That step in manufacturing insoles which consists in applying pressure to a marginal strip round one end of an insole and offsetting it by shifting said strip bodily into a higher plane than, but substantially parallel to, the plane of the adjacent marginal portions of the insole, while maintaining the upper surface of said strip substantially parallel to said planes, in order to compensate for an extra thickness of upper materials in the shoe in which the insole is to be incorporated.
16. That step in manufacturing insoles, each having a marginal sewing-rib and a feather outside said rib throughout the shank and forepart, which consists in applying pressure to the feather round the toe of the insole and molding it into a higher plane than the portion of the feather rearwardly of the toe.
